Primary Examiner — Daniel Bui*Assistant Examiner* — Khawaja Anwar(74) *Attorney, Agent, or Firm* — Ladas & Parry LLP(57) **CLAIM**

The ornamental design for support for refrigerator, as shown and described.

DESCRIPTION

FIG. 1 is a perspective view of a support for refrigerator, showing our new design;

FIG. 2 is a front elevation view thereof;

FIG. 3 is rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another perspective view thereof, in use condition. The broken lines are for environmental purposes only and form no part of the claimed design.
